INVENTOR.

UNITED STATES PATENT OFFICE.

FRANCIS E. BLISS, JR., OF CRANSTON, RHODE ISLAND.

DESIGN FOR A BRACELET.

SPECIFICATION forming part of Design No. 33,674, dated December 11, 1900.

Application filed November 3, 1900. Serial No. 36,429. Term of patent 3½ years.

To all whom it may concern:

Be it known that I, FRANCIS E. BLISS, Jr., a citizen of the United States, residing at Cranston, in the county of Providence and State of Rhode Island, have invented and produced a new and original Design for Bracelets, of which the following is a specification, reference being had therein to the accompanying drawings.

10 Figure 1 is a perspective view of my newly-designed bracelet, and Fig. 2 a transverse sectional view of the same on line *x-x* of Fig. 1.

As shown in the drawings, the leading or material feature of my design consists of 15 a bracelet having its exterior or ornament-bearing face *a* semicircular in cross-section,

flanked on either side by an annular plain bead *c*, while the inner or bearing surface of the bracelet *b* is flat and in cross-section forms the chord of an arc.

Having thus described my invention, what I claim as new, and desire to secure by Letters Patent, is—

The design for a bracelet as herein shown and described.

In testimony whereof I have affixed my signature in presence of two witnesses.

FRANCIS E. BLISS, JR.

Witnesses:

ROBT. L. STANTON,
HORATIO E. BELLows.
